UNITED STATES PATENT OFFICE.

PHILIP A. MYERS, OF ASHLAND, OHIO.

HAY-CARRIER TRACK.

SPECIFICATION forming part of Letters Patent No. 340,055, dated April 13, 1886.

Application filed October 30, 1885. Serial No. 181,395. (No model.)

To all whom it may concern:

Be it known that I, PHILIP A. MYERS, of Ashland, in the county of Ashland and State of Ohio, have invented a new and useful Improvement in Hay-Carrier Tracks; and I do hereby declare that the following is a full, clear, and exact description of the same.

In the putting up of hay-carrier tracks inconvenience frequently occurs with the forms of track heretofore known, in this, that the construction of these tracks requires the services of a skilled mechanician to put them in place. This entails considerable inconvenience and expense upon the farmer.

The object of the invention hereinafter set forth is to avoid this inconvenience and expense by providing a track which, without change, may be put up equally well, securely, and rigidly by any person, whether skilled laborer or not.

My invention is also equally applicable to the use of wood or iron in the construction of the track.

It consists, essentially, of a track composed of two parts, placed side by side and breaking joints where necessary, the parts being held together by clamps and bolts, with a space between, in which the suspending-bolts may be located at any convenient point in the direction of the length of the track.

The details of construction are also of my invention, and are fully set forth hereinafter.

In the accompanying drawings, Figure 1 shows in perspective a part of a wooden track made according to my invention. Fig. 2 shows the same in cross section. Fig. 3 is a perspective view of an iron track made in accordance with my invention. Fig. 4 is a cross-section of the same, showing the position of the suspending-rod and clamps; and Fig. 5 is a cross-section showing the clamps and bolt.

The wooden track is composed of beams A A, placed side by side, and preferably I provide these beams for the market in pieces, all of equal length. They are connected to each other by clamps a, which, as shown, are cast with small flanges at the ends and ridges 2 across the middle, on the same face of the clamp. The upper clamps are set flush with the upper and side surfaces in transverse gains cut in the timbers to leave the surface smooth for the track on which the wheel runs.

The lower clamps require no gains; but the outer flanges, 1, fit into a rabbet, 3, in the lower outer corner of the beam. The ridges 2, all 55 of the same width, lie in the space between the two beams, and determine its width, and the outer flanges hold the beams laterally. The central parts of the clamps may be thickened on the outside, as shown at 2, to compensate for the loss of metal at the hole through which the bolt 7 passes. These bolts simply connect the clamps, but in this as in the other form shown could be extended to form the suspending-rod, if in this form the gains happened to occur in the right place. This, however, would be unreliable, and the advantage arising from the slot or space left between the timbers is, that the suspending-rod 8 may be inserted therein at any point in the length of 70 the way, and being provided with a hook on its upper end to connect with the rafter or tie-beam, and a nut on its lower end, it holds the way securely suspended. For the points where the ends of two sections of beams 75 abut wider clamps, a', are provided, and these may have spurs 6, fitting notches in the beams. In making the track the gains are cut at regular intervals, so that the ends of the sections on one side, as shown in Fig. 1, will lie opposite a gain in the other side, and the other gains will coincide. The sections are all alike and of uniform size, and in putting up the track the workman has only to put the pieces in place and to clamp them together. 85 No cutting is required, except that it may be necessary to saw the overlapping section in two at the ends, and no tools are required other than a wrench and saw.

Figs. 3, 4, and 5 show how the same principle may be used in connection with iron beams. Here I use ordinary T-irons, A'A', instead of the wooden beams A A, and set these with the flanges to form vertical planes. The clamps a' are substantially the same in 95 form and function, having outer flanges, 11, and a central ridge, 12, these being formed by two kerfs on the under surface of the upper clamp, which, as well as the lower, fits on the flanges 13 of the iron. No countersink is here 100 necessary, as the carrier runs on the web 14, extending in a horizontal plane. The clamps may be set at any point, excepting that one is required precisely to cover the joint, as at

15, the others, 16, having bolts extended to form hooks, and being adjustable longitudinally to coincide with the tie-beams or other points of support for the hooks. The 5 iron beams, requiring no gains, may be supplied in pieces of different lengths, and may have short pieces, as *d*, Fig. 3, at the ends, to cause the others to break joints. The clamp-nuts on the upper and lower clamps are 10 precisely the same in both forms.

The precise form of the clamps is, manifestly, not material. They must be fitted to hold the two beams to each other and at proper distance apart, and may be greatly varied 15 without departing from the spirit of my invention so long as they are made to perform this function. Manifestly, also, the form of the beams may be varied without departing from the spirit of my invention. In putting up 20 either form the workman may attach the suspending-rod to the tie-beam or other support, insert its lower end between the beams of the track, and adjust it to vertical position before fixing it in place.

25 I claim as my invention—

1. The track for hay-carriers, formed of two beams placed side by side, with a space between them, combined with upper and lower clamps, the connecting-bolts passing vertically 30 through the clamps holding the two beams in fixed relation to each other, and suspending- rods inserted between the beams, substantially as described.

2. The track for hay-carriers, formed of two beams placed side by side, with a space between them, combined with upper and lower clamps having a ridge separating the beams,

the connecting-bolts passing vertically through the clamps holding the two beams in fixed relation to each other, and suspending- rods 40 inserted between the beams, substantially as described.

3. The track for hay-carriers, formed of beams placed side by side, with a space between, combined with upper and lower clamps 45 fitted to hold the beams in fixed relation to each other, and a bolt passing through the upper and lower clamps and extended to form a suspending-rod, and nuts to hold the clamps, all substantially as described. 50

4. The wooden beams made in pieces of uniform length, and having gains cut regularly therein, so as to cause the gains to coincide with each other and with the joints of the beam-sections, combined with clamps fitted to the gains, whereby the beams are made to present a smooth surface for the track, all substantially as described. 55

5. The wooden beams made in pieces of uniform length, and having gains cut regularly 60 therein, so as to cause the gains to coincide with each other and with the joints of beam-sections, in combination with clamps having ridges separating the beams, and with suspending-bolts in the space between the beams, 65 all substantially as described.

In testimony whereof I have signed my name to this specification in the presence of two subscribing witnesses.

PHILIP A. MYERS.
